UNITED STATES PATENT OFFICE.

FREDERICK W. CHESSON, OF WATERBURY, CONNECTICUT, ASSIGNOR TO
THE AMERICAN RING COMPANY, OF SAME PLACE.

DESIGN FOR A METAL MOUNT FOR BEDSTEADS.

SPECIFICATION forming part of Design No. 27,509, dated August 10, 1897.

Application filed December 26, 1896. Serial No. 617,112. Term of patent 7 years.

To all whom it may concern:

Be it known that I, FREDERICK W. CHESSON, a citizen of the United States, residing at Waterbury, in the county of New Haven and State of Connecticut, have invented and produced a new and original Design for Metal Mounts, of which the following is a specification, reference being had to the accompanying drawings, in which—

10 Figure 1 is an elevation, and Fig. 2 a plan, of my design.

The general configuration of the metal mount is round, and the leading features of my design consist in the convex or spheroidal body, the adjacent conical group of narrow convex parallel ribs, and the cove and larger bead, as shown.

The convex or spheroidal body is shown at *e*, the conical group of narrow convex parallel ribs at *a a'*, the adjacent coves at *b b'*, the large beads at *c c'*, the bands at 2 and 3, and the curved contracted ends at *d d'*.

What I claim is—

The design for a metal mount substantially as shown and described. 25

Signed by me this 17th day of December, A. D. 1896.

F. W. CHESSON.
